UNITED STATES PATENT OFFICE.

JAMES D. SMITH, OF CHICAGO, ILLINOIS, ASSIGNOR OF ONE-HALF TO FRANKLIN P. SMITH, OF CHICAGO, ILLINOIS.

WIRE-INSERTING MECHANISM FOR WIRE-MESH FABRICATED MATERIAL.

1,392,714.

Specification of Letters Patent.

Patented Oct. 4, 1921.

Application filed June 30, 1920. Serial No. 392,979.

To all whom it may concern:

Be it known that I, JAMES D. SMITH, a citizen of the United States, and a resident of Chicago, Cook county, and State of Illinois, have invented certain new and useful Improvements in Wire-Inserting Mechanism for Wire-Mesh Fabricated Material, of which the following is declared to be a full, clear, and exact description.

10 This invention relates to wire inserting mechanism for wire mesh fabricated material, such as guards, inclosures, screens, gratings and the like, and its principal object is to provide means for simplifying the operation of assembling wire mesh fabric with the border or frame that usually binds the edges of the wire mesh fabric.

15 In the manufacture of wire mesh guards, inclosures, screens, gratings and the like, a frame or border is secured to the edges of the wire mesh work, and the operation of assembling the frame or border and wire mesh work is ordinarily done by hand; it is an irksome and tedious task and requires 20 considerable time.

25 A common form of frame or border is made up of channel iron bars, which are perforated to receive the ends of the wires. The ends are thrust through the perforations by hand and are afterward clenched or bent back to fasten the wire mesh fabric to the frame. The present invention has been designed to enable the ends of the wire mesh fabric to be inserted in the perforations by unskilled labor and in a fraction 30 of the time ordinarily taken by more skilled workmen.

35 The invention consists in the several novel features hereinafter fully set forth and 40 claimed.

The invention is clearly illustrated in the drawings accompanying this specification, in which:—

45 Figure 1 is a front view of an apparatus embodying a simple form of the present invention, Fig. 2 is a plan thereof, Fig. 3 is a detail side view of a latch forming part of the apparatus, the frame being shown in vertical section, taken on the line 3—3 of 50 Fig. 1; Fig. 4 is a vertical cross section taken on line 4—4 of Fig. 2; Fig. 5 is a horizontal section taken on line 5—5 of Fig. 4 but showing the parts in a different position; Fig. 6 is a fragmental rear view of

the guide for the wire mesh fabric ends and 55 Fig. 7 is a detail cross section taken on line 7—7 of Fig. 6.

Referring to said drawings, which illustrate a simple embodiment of the present invention, the reference character 8 designates 60 a work table which may be supported by legs 9. The table may be of any suitable size to support wire mesh fabric of large or small dimensions. Adjacent one edge of the table 8 is a wire guide 10 for guiding the 65 ends of the wires that are to be inserted, and extending parallel with said wire guide is an inserter bar 11, which may be in the form of an angle iron bar formed with notches 12 in its upper edge that have upstanding fingers 13 between them that are arranged to engage with the wire mesh fabric, to hold it in shape while the ends of the wires are being inserted in the perforations of the frame bars. Means are provided for moving said inserter bar 11 toward and away from the wire guide 10, and the simple means shown, comprises a plurality of slotted rods or bars 14, guided to move at right angles to the wire guide 10, 80 levers 15 and a spring 16. Conveniently the rods or bars 14 are slidably supported by plates 17 secured to the upper face of the table 9 and guided thereon by bolts 18 that are secured in the plates 17 and extend 85 through the slots of the bars 14. The levers 15 may be mounted on a shaft 19 supported by brackets 20 that extend down from the table, and the front ends of the levers may be connected by a rod or bar 21 that acts 90 as a connecting handle for the several levers 15. The arms 22 of the levers 15 are connected to the rear ends of the bars 14 by pins or bolts, and the spring 16 is connected to a plate 17 and to a long arm 23 95 of one of the levers 15. By pressing down on the handle 21, all of the levers 15 are moved down simultaneously and all of the bars 14 are thereby moved forward in unison, thereby moving the inserter bar 11 and 100 therewith the wire mesh fabric toward the wire guide 10.

In the simple form illustrated said wire guide compresses two separable, companion guide bars 24 and 25, the bar 24 being a 105 stationary one secured to the table 9, and the upper one 25, being vertically movable and guided in ways formed in upright guide

posts 26, that are secured to and project up from the table 8. For the convenience of handling the upper guide bar 25, I have provided a lattice like frame 27, which is secured to the upper guide bar 25, and connected to counter weights 28 by cords or cables 29 trained around pulleys 30, supported at the upper ends of the guide posts 26.

The wire guide 10 is formed with flaring 10 eyes or guide ways 31, through which the wire ends of the wire mesh fabric are guided to the holes of the frame bar when the fabric is moved forward by the inserter bar 11. Said eyes or guideways are formed 15 by making oppositely disposed V shaped notches in the meeting faces of the guide bars 24 and 25, the wider ends 31^a of the notches being on the far side of the guide bars and the narrow ends 31^b of the notches 20 being on the near side. The small or narrow ends 31^b of the notches are preferable semi-circular in shape, whereby, when the two guide bars are brought together the near ends of the opposite notches may form 25 circular openings, and said openings are spaced equidistant and the distance apart is determined by the size and shape of the mesh of the wire fabric and the corresponding spacing of the perforations in the frame 30 bars of the finished material.

The front edge and top of the table 8 may be protected by an angle iron bar 41 if desired, and the lower guide-bar 24 may be fastened to said bar. To insure proper register between the opposing notches of the guide-bars I provide tapered dowels or other guide-pins 32 in the lower guide-bar 24 which enter sockets or recesses 33 in the upper guide-bar, and for the purpose of 40 locking the two guide-bars together during the operation of inserting the wires, I provide latches 34, on the guide posts 26, which may swing over the upper guide-bar 25, or over some part of its frame 27 (see Fig. 3), 45 whenever the upper guide-bar 25 has been brought down on the lower guide-bar.

A fragment of a sheet or piece of wire mesh fabric is illustrated at 35 in Figs. 4 and 5, and may be of the ordinary "diamond" mesh type, or square mesh, and may be made of round or flat wire as desired. One step in the preparation of diamond mesh fabric for the operation of assembling it with the frame is to bend the ends of the 55 wires straight out at places along the margin of the sheet or piece of fabric, and, as shown, the ends are bent outward at the places where the wires intersect each other nearest the margin of the sheet or piece of 60 fabric, so as to form laterally bent end portions 36. When the apparatus is used on square mesh fabric, this bending operation is omitted.

The frame bar for one edge of the sheet 65 or piece of fabric is shown at 37 and may be

in the form of a channel iron bar as shown. It is formed with a row of perforations 38 spaced equidistant at the proper places to receive the bent end portions 36 of the wire fabric. A support is provided for holding 70 the frame bar 37 in position in front of the wire guide 10 and said support may comprise brackets 39 secured to the table 8 and having horizontal parts upon which the bar 37 lies, and upright parts that hold the bar 75 37 against sidewise movement. A stop or gage 40 secured to the table 8 may be used to locate the frame bars 37 properly with the perforations thereof in register with the small ends of the guide openings or eyes 31. 80

In the operation of the apparatus, the sheet or piece of wire mesh fabric is laid on the table 8 in engagement with the inserter bar, 11, a row of intersections of the wires being placed in the notches of the inserter bar as shown. When properly placed on the inserter bar, the wire mesh fabric is thereby held in shape with the wire ends 36 pointed toward the eyes or guide openings 31. The upper guide bar 25 having 90 been lowered and secured in place, and a perforated frame bar 37 having been put in place on the brackets 39, the handle 21 is swung down, and the rods 14 and inserter bar 11 thereby moved forward, carrying 95 forward the wire mesh fabric. The wire ends 36 enter the flaring eyes or guide openings 31 and are guided by the tapered walls thereof to the holes in the frame bar 37. After the ends have been passed through 100 the holes of the frame bars, the latches 34 are disconnected from the upper guide-bar 25, the latter raised and the wire mesh fabric with the attached bar lifted from the table. The handle 21 is then released, permitting the spring 16 to return the levers 15, rods 14 and inserter bar 11 to their retracted position. The wire ends are afterward bent back against the frame bar to fasten it to the wire mesh fabric as usual. 110

The eyes or guide-ways 31 and fingers of the inserter bar are spaced to conform to the shape of the mesh work and spacing of the wires of the fabric, and the apparatus may be provided with several guides 10 and 115 inserters 11 arranged for use in connection with several shapes and spacings of wire mesh fabric.

More or less variation of the exact details of construction is possible without departing from the spirit of this invention; I desire, therefore, not to limit myself to the exact form of the construction shown and described, but intend, in the following claims, to point out all of the invention disclosed herein. 120

I claim as new and desire to secure by Letters Patent:

1. Apparatus for use in assembling wire mesh fabric with frame bars, comprising a 130

- wire guide having tapering wire guiding eyes, an inserter bar having wire mesh engaging fingers, and actuating means for said inserter bar.
- 5 2. Apparatus for use in assembling wire mesh fabric with perforated frame bars, comprising a wire guide, consisting of upper and lower, separable guide bars, provided with oppositely disposed tapered 10 guide ways, and wire inserting mechanism having wire mesh engaging fingers.
3. An apparatus for use in assembling wire mesh fabric with perforated frame bars, a wire guide for guiding the wires to 15 the perforations of the frame bars, comprising upper and lower separable, oppositely notched, guide bars, the notches being of tapering formation.
4. Apparatus for use in assembling wire 20 mesh fabric with perforated frame bars, comprising upper and lower separable, oppositely notched bars, the opposing notches forming tapering guide-ways, a support for holding a perforated frame bar in position 25 in front of said guide bars with the perforations of the frame bar in register with the guide-ways, and an inserter having fabric adjusting members.
5. Apparatus for use in assembling wire mesh fabric with perforated frame bars, 30 comprising upper and lower, separable, oppositely notched bars, the opposing notches forming tapering guide-ways, a support for holding a perforated frame bar in position 35 in front of said guide bars with the perforations of the frame bar in register with the guide-ways, an inserter bar having fabric adjusting fingers and an actuating lever operatively connected to said bar.
6. Apparatus for use in assembling wire 40 mesh fabric with perforated frame bars, comprising upper and lower, separable, oppositely notched bars, the opposing notches forming tapering guide-ways, a support for holding a perforated frame bar in position 45 in front of said guide bars with the perforations of the frame bar in register with the guide-ways, an inserter bar having fabric adjusting fingers, means for guiding said inserter bar, and a lever for actuating said 50 inserter bar.

JAMES D. SMITH.
